Patented Feb. 20, 1917.

FIG. 1.

FIG. 2.

FIG. 3.

INVENTOR

Michael A. Droitcour,
By C. Wm. C. Crampton,
his attorney.

UNITED STATES PATENT OFFICE.

MICHAEL ANDREW DROITCOUR, OF DELPHOS, OHIO.

SHOO-FLY FOR PRINTING-PRESSES.

1,216,668.

Specification of Letters Patent. Patented Feb. 20, 1917.

Application filed January 6, 1916. Serial No. 70,668.

To all whom it may concern:

Be it known that I, MICHAEL A. DROITCOUR, a citizen of the United States, and a resident of Delphos, in the county of Van Wert and State of Ohio, have invented a certain new and useful Shoo-Fly for Printing-Presses; and I do hereby declare the following to be a full, clear, and exact description of the invention, such as will enable others skilled in the art to which it pertains to make and use the same, reference being had to the accompanying drawings, and to the characters of reference marked thereon, which form a part of this specification.

This invention relates to printing presses, and particularly to a shoo-fly attachment therefor, which is carried by the impression cylinder and is automatically operable to lift the forward edge of a sheet from the cylinder when released by the gripper-means, thus facilitating a passage of the sheet from the cylinder onto the sheet delivery means after the printing operation.

The object of my invention is the provision of a shoo-fly mechanism of the character described, which is operatively connected to and is actuated by the gripper means to lift the forward edge of a sheet when the gripper means is operated to release the sheet.

The invention is fully described in the following specification, and while, in its broader aspect, it is capable of embodiment in numerous forms, a preferred embodiment thereof is illustrated in the accompanying drawing, in which,

Figure 1 is a perspective view of the impression cylinder of a printing press with my invention associated therewith, and Figs. 2 and 3 are fragmentary end elevations thereof, with the gripper means and shoo-fly means in normal position in the former, and moved from such position in the latter.

Referring to the drawings, 1 designates the platen or impression cylinder, 2 the feed table, and 3 the sheet delivery means of a printing press, said delivery means having a set of fingers 3^a projecting from the receiving end thereof adjacent to and substantially in tangential relation to the top portion of the cylinder in position for a sheet to pass thereover from the cylinder when released by the gripper means, as is well understood in the art.

The gripper-fingers 4 are carried by a

shaft 5, which is mounted for rocking movements in the cylinder ends, the shaft being rocked to alternately grip and release a sheet at predetermined points in a revolution of 60 the cylinder. The mechanism employed for rocking the gripper-shaft is not shown as it, in itself, forms no part of the present invention, and the different mechanisms employed on different types and styles of presses are 65 well understood by persons skilled in the art.

The shoo-fly fingers are designated 6 and are arranged in alternating relation to the gripper-fingers 4 and carried at their inner ends by a rocker-shaft 7, that is journaled at its ends in the respective cylinder ends. An arm 8 is carried by the shaft 7 at one end thereof and has a rod 9 pivotally extending from its free end and projecting 75 through a guide stud 10 on the adjacent cylinder end. A coiled compression-spring 11 is mounted on the rod 9 with one end thrust against the stud 10 and its other end thrust against a pin 12 on the rod, said 80 spring urging a rocking of the shaft 7 in a direction to retain the free ends of the shoo-fly fingers against the edge or portion of the cylinder periphery to which the forward edge of a sheet is gripped by the gripper-fingers 4. When a sheet is gripped to the cylinder the free ends of the shoo-fly fingers are disposed below or at the inner side of the gripped edge of the sheet, whereby an outward movement of the shoo-fly fingers 90 will effect a lifting or outward throwing of the sheet edge from the cylinder, as shown in Fig. 3.

The means employed for imparting rocking movements to the shoo-fly shaft 7 from 95 and simultaneous with the initial rocking movements of the gripper-shaft 5, whereby the forward edge of a sheet is raised or moved outward from the cylinder as it is released by the gripper-fingers, will now 100 be described.

The gripper-shaft 5 is provided near one end thereof, in the present instance, with a collar or enlargement 13, which is fixed thereto and is provided on its outer side 105 with respect to the cylinder with a radially projecting tooth or spur 14. A rocker-arm 15 is fixed to the shoo-fly shaft 7, in transverse alignment with the collar 13, and has a trip-finger 16 pivotally projecting from 110 its outer end in substantially longitudinal relation to a circle concentric to the axis of

the gripper-shaft 6 and adapted to yieldingly bear inward against the outer end of the tooth or spur 14 when the gripper-fingers 4 are in sheet gripping position. The 5 trip-finger 16 is provided at the rear of its free end with a shoulder 17, which is properly positioned for the tooth or spur 14 to have side thrust contact therewith when the shaft 5 is rocked to move the gripper- 10 fingers outward to release a sheet and to impart a simultaneous rocking movement to the shoo-fly shaft 7 through said trip-finger and the arm 15. When the tooth or spur 14 has turned a predetermined distance 15 it will have withdrawn from engagement with the shoulder 17, thereby permitting the shoo-fly shaft and attached parts to return to normal position under the influence of the spring 11. A spring-finger 20 18 is carried by the arm 15 and has its free end bearing inward against the outer side of the trip-finger 16 to yieldingly hold its free end in inward bearing engagement with the collar 13 or its tooth 14.

25 It is evident that an initial outward rocking movement of the gripper-shaft 5 from sheet gripping position will effect a simultaneous raising of both the gripper and shoo-fly fingers to cause a releasing of the 30 sheet edge by one and an outward moving of the released sheet edge from the cylinder periphery by the other, and that when the gripper shaft has reached a predetermined point in its outward turning movement the 35 tooth 14 will slip from engagement with the shoulder 17 on the trip-finger 16, thus permitting the shoo-fly parts to snap back to normal position under the action of the spring 11.

40 It will be understood in the operation of the invention that when the cylinder, in its impression revolution, has reached a point at which the forward edge of the printed sheet carried thereby is adjacent to 45 the delivery fingers 3^a, the gripper-shaft 5 is automatically operated to move the gripper-fingers to release the engaged sheet and that simultaneously with the initial releasing movement of the gripper-fingers the 50 shoo-fly means will be operated to raise the forward edge of the sheet, which is designated *a* in Fig. 3, to insure the passage of such sheet over the delivery fingers 3^a. When the edge of the sheet has been raised 55 a predetermined distance by the shoo-fly fingers, the trip-finger 16 is automatically released from engagement with the tooth or spur 14 on the gripper-shaft 5, thus permitting the shoo-fly parts to return to their 60 normal position. The turning of the gripper-shaft 5 on its axis of rotation is continued for a predetermined distance after the shoo-fly means has been released from engagement therewith, as is well understood in the art. 65

It is apparent that I have provided a shoo-fly operating mechanism which is simple and inexpensive in its construction, and is connected to and operated directly by the gripper-means, so that the movements 70 of the shoo-fly means are positive and properly timed with the sheet releasing movements of the gripper means.

I wish it understood that my invention is not limited to any specific construction, arrangement or form of the parts, as it is capable of numerous modifications without departing from the spirit of the claims. 75

Having thus described my invention, what I claim as new, and desire to secure by Letters Patent, is,—

1. In combination, sheet gripping means, shoo-fly means, and means having connection with and operated by sheet releasing movements of said gripping means to impart predetermined movements to said shoo-fly means. 85

2. The combination with the rocker-shaft of a sheet gripping mechanism, of shoo-fly means having a rocker-shaft and shoo-fly 90 fingers projecting therefrom, and means having connection with and operated by initial sheet releasing rocker movements of said first rocker-shaft to impart predetermined rocking movements to said shoo-fly rocker-shaft. 95

3. The combination with sheet-gripper means of a printing press, said means having a rocker part, of shoo-fly means having a shoo-fly finger rocker-shaft, an arm projecting from said rocker-shaft, and a trip-finger connecting said arm and rocker part and operable to impart predetermined rocking movements to said rocker-shaft when 100 said rocker part is rocked. 105

4. In a printing press, an impression cylinder, a pair of rocker-shafts carried by said cylinder, one having sheet gripping fingers and the other shoo-fly fingers projecting therefrom, and means connecting said shafts 110 and operable to impart predetermined rocking movements to one when the other has predetermined rocking movements. 115

5. In combination, a cylinder, a sheet-gripper mechanism carried thereby and having a rocker-shaft, shoo-fly means carried by the cylinder and having a rocker-shaft, and means connecting the rocker-shafts of said mechanism and shoo-fly means and automatically operable to communicate predetermined rocking movements to the shoo-fly means when the gripper mechanism shaft is rocked and to release the connection between said rocker-shafts when the rocker-shaft of the shoo-fly means has been rocked a predetermined extent. 120

6. In combination, a cylinder, a sheet-gripper mechanism carried thereby and having a rocker-shaft, a shoo-fly means carried by said cylinder and having a rocker-shaft, 125

means operable to normally maintain the shoo-fly means in one position of its movement with respect to the cylinder, and means connecting the rocker-shafts of said gripper mechanism and shoo-fly means and operable to move the shoo-fly means a predetermined distance from normal position when the rocker-shaft of said mechanism has sheet releasing movements imparted thereto and then to release said shoo-fly means to permit it to return to normal position.

7. The combination with the cylinder of a printing press, and sheet-gripper means carried thereby and having a rocker-shaft, of a tooth projecting from said rocker-shaft,

a shoo-fly means carried by said cylinder and including a rocker-shaft and shoo-fly fingers projecting from said shaft, means acting on the shoo-fly means to normally retain it in one position of its movement with respect to the cylinder, an arm projecting from the shoo-fly shaft and a spring pressed finger pivotally projecting from said arm and having a part for coacting with said tooth whereby an initial rocking of the gripper-shaft from sheet-gripping position will effect a rocking of the shoo-fly means from normal position and then release it.

In testimony whereof, I have hereunto signed my name to this specification.

MICHAEL ANDREW DROITCOUR.
